UNITED STATES PATENT OFFICE.

JOSEPH P. FLECKENSTEIN, OF BETHLEHEM, PENNSYLVANIA, ASSIGNOR, BY MESNE
ASSIGNMENTS, TO BETHLEHEM STEEL COMPANY, A CORPORATION OF PENNSYLVANIA.

FROG.

1,271,556.

Specification of Letters Patent.

Patented July 9, 1918.

Application filed August 22, 1916. Serial No. 116,246.

To all whom it may concern:

Be it known that I, JOSEPH P. FLECKENSTEIN, a citizen of the United States, residing at Bethlehem, in the county of Northampton and State of Pennsylvania, have invented certain new and useful Improvements in Frogs, of which the following is a specification.

Cast steel frogs are commonly of shell-like formations, the under side thereof being usually cored longitudinally beneath the point, leaving the point-supporting top wall relatively thin. As the body of the frog and hence the bottom cavity thereof are of greatest width in the portion carrying the frog point, the point-supporting top wall in many cases yields under the excessive weight of the rolling stock, the most pronounced strain resulting from the pounding of the wheels as they pass from the wing rails onto the frog point.

The primary object of the present invention is to provide an efficient reinforcement for the point carrying portion of the frog, the reinforcement extending longitudinally of the frog point, whereby the latter is directly sustained by the cross ties or other foundation on which the frog is laid. The reinforcement is preferably formed in sections rather than in one continuous length to prevent fracture that might result from contraction when the casting cools, the construction being such that the reinforcement is quite as effective as though there were no break or interruption therein.

In the accompanying drawings, Figure 1 is a top plan of the improved frog, showing the track rails connected to opposite ends thereof. Fig. 2 is a central longitudinal section of the frog. Fig. 3 is an inverted plan of the frog. Figs. 4 and 5 are cross sections taken on lines 4-4 and 5-5, respectively, of Fig. 1.

The frog of the present invention is known as a solid manganese frog, and consists of a relatively thin cast steel shell. The body of the frog is widest intermediate its toe end 2 and heel end 3, this being the portion of the frog which carries the integral frog point 4. By referring to Figs. 2 and 4, it will be seen that the body is cored or recessed upwardly at 5, so that the top wall 6 which supports point 4, and which is formed with usual longitudinal grooves 6' at opposite sides of the point, is relatively

thin, and the same is true of the walls 7 which merge into the lateral bottom flanges 8.

To strengthen the point-supporting portion of the body without unduly increasing the weight of the frog as a whole and hence without unnecessary consumption of costly steel, the top wall 6 of the bottom recess is reinforced by the relatively thin depending rib formation 9 located beneath and extending longitudinally of the frog point. To prevent fracture of the relatively thin reinforcement incident to contraction of the casting when cooling, it is formed in relatively short lengths, with one end of each length formed with the curved oppositely extending flanges 10 which are integral with the rib and with the top and side walls of the bottom cavity. The curvature of flanges 10 is such that the unflanged end of the next adjacent rib section extends therebetween, so that the strengthening effect is the same as though the rib were continuous or unbroken. Rib 9 and flanges 10 are coincident with the bottom plane of the frog and hence rest directly on the foundation on which the frog is laid.

With a hollow or cast steel frog constructed in accordance with the present invention, the part thereof subjected to the greatest strain, *i. e.*, the point-carrying part, is so strengthened and reinforced as to render the structure as permanent and wear-resisting as though it were not cored on its under side.

I claim:

1. A frog recessed at its under side and at its top formed with a frog point, ribs depending from the top wall of the recess and arranged in line with each other and extending longitudinally of the frog point, and oppositely curved laterally extending flanges connecting one end of each longitudinal rib with the side walls of the recess, the unflanged end of the longitudinal rib extending between the curved lateral flanges of the next adjacent rib.

2. A cast metal railroad frog comprising a floor portion, spaced longitudinally-extending lateral web portions supporting the floor portion, tread portions rising from the floor portion, and converging web portions extending beneath the floor portion and connected at their outer ends to said lateral web portions and connected together at their inner ends.

3. A cast metal railroad frog comprising a floor portion, spaced longitudinally-extending lateral web portions supporting the floor portion, tread portions rising from the floor portion, and converging web portions extending beneath the floor portion and connected at their outer ends to said lateral web portions and terminating at their inner ends in a single web portion extending longitudinally of the frog between said lateral web portions, said converging web portion and said single web portion supporting said floor portion and the tread portions rising therefrom.
- 15 4. A cast metal railroad frog comprising a floor portion, spaced longitudinally-extending lateral web portions supporting the floor portion, tread portions rising from the floor portion, and a plurality of pairs of converging web portions extending beneath the floor portion and connected at their outer ends to said lateral web portions, the web portions of each of said pairs terminating at their inner ends in a single web portion extending longitudinally of the frog between said lateral web portions, one of said single web portions terminating between the web portions of one of said pairs in spaced relation thereto, and said single web portions and 25 said converging web portions supporting said floor portion and the tread portions rising therefrom.
5. A cast metal railroad frog comprising a floor portion, wing rail tread portions rising from the respective sides of said floor portion, a pointed tread portion rising from

the central portion of said floor portion, lateral web portions extending longitudinally of the frog beneath said wing rail tread portions and supporting the same and said floor portion, and converging web portions extending beneath the floor portion and connected at their outer ends to said lateral web portions and terminating at their inner ends in a single web portion extending longitudinally of the frog beneath and supporting said pointed tread portion.

6. A cast metal railroad frog comprising a floor portion, wing rail tread portions rising from the respective sides of said floor portion, a pointed tread portion rising from the central portion of said floor portion, lateral web portions extending longitudinally of the frog beneath said wing rail tread portions and supporting the same and 40 said floor portion, and a plurality of pairs of converging web portions extending beneath the floor portion and connected at their outer ends to said lateral web portions, the web portions of each of said pairs terminating at 45 their inner ends in a single web portion extending longitudinally of the frog beneath and supporting said pointed tread portion, one of said single web portions terminating between the web portions of one of said pairs in spaced relation thereto.

In testimony whereof, I affix my signature in presence of two witnesses.

JOSEPH P. FLECKENSTEIN.
